UNITED STATES PATENT OFFICE.

GEORGE THOMPSON, OF MOUNT VERNON, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed November 3, 1923. Serial No. 672,456.

This invention relates to automatic telephone exchange systems and more particularly to exchange systems in which operators are equipped with calling dials.

5 It is the object of this invention to provide a link circuit which will be commonly available for use, both by calling subscribers and by operators, which will discriminate between various classes of incoming lines, and which will function accurately with either class of incoming lines.

By the use of this invention a more economical grouping of selectors may be effected since it will no longer be necessary to provide separate groups of districts and associated groups of senders to serve subscribers and separate groups to serve operators.

20 A feature of this invention is the provision of means to differentiate in the sender between an operator's call and a subscriber's call.

25 A further feature resides in the method of cancelling the selection of talking battery ordinarily controlled by the office code dialled and substituting another selection when the call is being made by an operator.

30 A still further feature may be found in the use of a panel type selector for seizing the sender.

Other features are shown in the novel circuit arrangements which will be more apparent from the following description and appended claims.

35 Reference may now be made to the accompanying drawing in which Fig. 1 shows the circuit of a line switch individual to a subscriber's line and a diagrammatic representation of a second line switch individual to a trunk extending to an operator's position. Only that portion of an operator's circuit necessary to an understanding of the invention has been shown.

40 In Fig. 2 is shown the circuit of a district selector switch, its associated sender selector and a controlling sequence switch therefor.

45 Fig. 3 shows the class circuit, its controlling sequence switch and various auxiliary relays.

50 Fig. 4 shows a register control switch and one of the register switches.

55 In Fig. 5, the remaining register switches are shown, and there are indicated diagram-

matically portions of a translator switch 55 which is positioned under the joint control of the first two registers.

Fig. 6 shows the sender circuit including the counting relays and a controlling sequence switch together with various relays. In this figure are shown, within the dotted section, contacts controlled by the class sequence switch of Fig. 3.

60 Fig. 7 shows an arrangement of letters and numerals on a dial suitable for use with the system of the type disclosed in this application.

65 Fig. 8 shows the relation to one another in which the various sheets should be placed in order to coordinate them properly.

70 Fig. 9 shows a schematic arrangement of trunk terminal grouping when panel type selectors are used for making sender selection.

75 Each district circuit is equipped with two elevators, one to make the usual district selections and the other to select an idle sender. In the drawing, 51 is a district elevator and 52 a sender selector elevator. The former hunts over the terminals in groups 54, while the latter is confined to terminals in groups 53 and 55. Each sender has six terminals and, since the district elevator brushes are arranged for contact with only 3 terminals, it is necessary to use two 80 brush sets for the sender selector. One set is arranged to make contact with three terminals in group 53 and the other set to make contact with three terminals in group 55. It was not thought necessary to show this 85 arrangement in the circuit diagram on Fig. 2. The six terminals have been shown in one line for the sake of simplicity.

90 It will first be assumed that a call is initiated by the subscriber at substation 1.

95 When the subscriber at substation 1 removes his receiver from the switchhook, a circuit is completed from grounded battery, through the winding of line relay 2, inner lower armature and back contact of cut-off relay 3, through the loop of the calling substation line, upper armature and back contact of relay 3, to ground. Line relay 2 is energized in this circuit and attracts its armatures. Since the test brush 5 is in engagement with its normal contact, and since its normal contact is connected to ground, the energization of line relay 2 completes a 100 105

2

circuit from grounded battery, winding, armature and back contact of stepping magnet 4, lower armature and back contact of cut-off relay 3, left hand armature and 5 front contact of line relay 2, conductor 15, test brush 5, normal terminal to ground. Magnet 4 is energized and upon energization interrupts its own circuit to release its armature and advance the line switch into 10 its first off-normal position. As soon as the line switch makes its first step off normal, contact 13 closes and off-normal spring 14 releases and engages its lower contact. Off-normal contact 14 removes the control of the 15 cut-off relay from any line which may be calling and supplies its battery to test terminal 16 to render the calling line busy to other calling subscribers. The test terminals of trunks extending to busy district 20 circuits will be characterized by the presence of ground potential on such test terminals as will be evident from the following description. As long as test brush 5 engages contacts of busy trunks, ground will be supplied over conductor 106 to conductor 15 and stepping magnet 4 will continue to interrupt its own circuit causing the advance of the line switch. As soon as test brush 5 engages a terminal on which there is no 25 ground potential the circuit of magnet 4 is opened. Then the switch is brought to rest with its brushes on the terminal set of an idle trunk leading to an available district selector. 30

35 It should be noted that during the operation of this switch a circuit is in existence for cut-off relay 3 extending from ground, upper and lower windings of cut-off relay 3, right winding of line relay 2, right armature and front contact of relay 2, left armature and front contact of relay 2, to grounded battery, through the winding of magnet 4. Cut-off relay 3, however, cannot be energized in this circuit since its winding is short circuited by the direct ground supplied to conductor 15 by means of test terminals 9. As soon as the brush set comes to rest on the selected terminals a circuit is completed from grounded battery, resistance 40 199, contacts of sequence switch spring 198, outer armature and back contact of relay 102, conductor 106, terminal 9, brush 5, conductor 15, right winding and armature and front contact of relay 2, windings of 45 cut-off relay 3 to ground. The presence of battery potential on terminal 9 short circuits magnet 4 and allows cut-off relay 3 to operate. The operation of cut-off relay 3 causes the deenergization of line relay 2. 50

55 A circuit is then completed from grounded battery winding of relay 102, armature and back contact of relay 139, lower right contact of sequence switch spring 103, conductor 104, terminal 11, brush 7, lower middle armature and front contact of relay 3, 60

lower winding of relay 3 to ground. Relay 102 is energized and at its outer armature and front contact supplies ground to test conductor 106 and its associated contacts to render this trunk non-selectable to other 70 hunting line switches. The energization of relay 102 also completes a circuit from grounded battery, left winding of relay 107, upper contact of sequence switch spring 108, lower right and upper left contacts of sequence switch spring 109, inner armature and front contact of relay 102 to ground. Relay 107 energizes in this circuit. A locking circuit for this relay extends from grounded battery, right winding, inner 80 armature and front contact of relay 107, conductors 110 and 111, lower right contact of sequence switch spring 112, lower right contact of sequence switch spring 113, conductors 114 and 181, commutator segment 182, brush 183 in its normal position to ground. Relay 107 also completes a circuit from grounded battery, power magnet of sequence switch 100, upper left contact of sequence switch spring 116, left armature and front contact of relay 107 and lower contact of sequence switch spring 117 to ground for moving this sequence switch out of position 1 and into position 2 under control of its master spring contact 101. 90

In position 2 of sequence switch 100, a circuit is completed for selecting an idle sender. A circuit for sender selector up-drive magnet 118 is completed from grounded battery, winding of magnet 118, lower left contact of sequence switch spring 120, left armature and front contact of relay 107 and the lower contact of sequence switch spring 117 to ground. The energization of magnet 118 causes the upward movement of the sets of sender selector brushes over the terminals in groups 53 and 55. As soon as the commutator brush 183 leaves segment 182 the holding circuit for relay 107 is transferred from ground on brush 183 to ground on the terminals of busy senders. When an idle sender is found the absence of ground on the test terminal of said sender breaks the locking circuit of relay 107. This relay deenergizes, opening the circuit of updrive magnet 118 and bringing the sender selector brush sets to rest on the terminals of the idle sender. Relay 107 upon deenergizing, also completes a circuit from grounded battery power magnet of sequence switch 100, lower left contact of sequence switch spring 116, left armature and back contact of relay 107, lower contact of sequence switch spring 117 to ground for moving its sequence switch out of position 2 into position 3. 100

105 During the hunting movement of the sender selector a circuit exists from grounded battery, windings of updrive magnet 118 and relay 121, left contacts of se- 110

quence switch spring 122, conductor 105, outer left armature and front contact of relay 102 to ground. The presence of direct ground at sequence switch spring 120 shunts relay 121 at this time to prevent its operation. As soon as relay 107 is deenergized, however, this shunt is removed and relay 121 energizes to connect the controlling leads to the selected sender. Relay 121 at its inner 10 left armature supplies ground to the terminal associated with test brush 115 to render the sender non-selectable by other selectors. As soon as the sender has been seized and relay 121 has operated, a circuit is completed 15 from grounded battery, winding of relay 202, lower right and upper left contacts of sequence switch spring 203, conductors 204 and 205, test brush 115 and its associated contact, conductor 114, inner left armature 20 and front contact of relay 121, to ground. Relay 202 is energized in this circuit, and completes a circuit from grounded battery, winding of sequence switch magnet 200, upper right contact of sequence switch 25 spring 219, inner right armature and front contact of relay 202 to ground, moving this sequence switch out of position 1 into position 3 under control of its master sequence switch spring 201.

30 The primary circuit of the induction coil by means of which the dialing tone is supplied to the calling subscriber extends from a suitable source of tone through the left hand winding of relay 213, conductor 214, register brush 500 in its normal position, conductor 501, outer right armature and back contact of relay 502, to ground at the right armature and back contact of slow-to-release relay 503. Current in this circuit is 35 induced into the receiver of the calling subscriber's substation set over a circuit extending from grounded battery, winding of line relay 215, conductor 216, sender selector brush 123 and its associated contact, outer 40 left armature and front contact of relay 121, conductor 124, lower left contact of sequence switch spring 125, conductor 126, through the contact of the line switch, to the calling subscriber's station, through the tip contacts 45 of the line switch, conductor 127, upper left contact of sequence switch spring 128, conductor 129, sender selector brush 130 and its associated contacts, conductor 131, right armature and back contact of relay 213, middle winding of relay 213, conductor 298, 50 progression switch brush 599, in its normal position, to ground. When the calling subscriber hears this dialing tone he operates his substation dial 32 to send out series of 55 impulses to the set of registers in the selected sender. It will be assumed that the line to be selected is one which terminates in a full mechanical exchange which may be selected directly by means of a district se-

lector and an office selector. In this case the registers and class registers will have to be set in such a position as to control brush and group selections at the district, office and incoming switches and brush, group and line selection at the final switch. 65

Assuming that the wanted line is Grand 5678, an inspection of the dial in Fig. 7 will show that the subscriber will first insert his finger in the hole containing the letter "G" and the digit 3 to send 4 impulses. He will 70 then operate his dial to send the letter "R" or 8 impulses after which he will send series of 6, 7, 8 and 9 impulses, respectively. 75

In order to prevent confusion as to which switches the various brushes and contact 80 arcs shown in Figs. 4 and 5 are related, the brushes belonging to the progression switch or side switch have been indicated by the letters SS; the arms belonging to the register which is operated in response to the first 85 series of impulses of the office code have been designated by the letter A; the brushes belonging to the register which is operated in response to the second series of impulses, by the letter B; the brushes of the thousands register are identified by the letters TH, and those of the hundreds, tens and units registers have been designated by the letters H, T and U, respectively. 90

95 Returning to the operation, relay 215 is energized upon completion of the above traced dial tone circuit and causes in turn the energization of slow-to-release relay 217 which in turn causes the energization of relay 218. The first interruption due to the 100 operation of the calling subscriber's dial causes the deenergization of relay 215. This interruption being of short duration, however, relay 217 holds over, thereby maintaining relay 218 energized. Upon the deenergization of relay 215 a circuit is completed from grounded battery, through resistance 504, winding of relay 503, conductor 523, winding of magnet 505, which controls the advance of the A register, conductor 506, side switch brush 507 and its normal contact, conductor 508, left armature and front contact of relay 218, armature 105 and back contact of relay 215, to ground. Stepping magnet 505 is energized to cause 110 the register to advance one step. Relay 503 is energized and being slow-to-release, remains energized until the completion of a series of impulses. In response to the first 115 series of impulses relay 215 is deenergized four times and upon each deenergization causes the stepping magnet 505 to advance the register brushes one step. Upon completion of the series of impulses the A register 120 will be in its fourth off-normal position. 125

At the termination of the series of impulses, relay 215 maintains its armature attracted for a relatively long period of time

with the result that relay 503 is deenergized. Upon the deenergization of relay 503, a circuit is closed from ground at the right armature and back contact of relay 503 to the winding of relay 519, conductor 509, upper left and lower right contacts of sequence switch spring 220, conductor 221, through the units register brush 512, through its normal contacts, and thence to brushes 513, 514, 515, 516 and the respective brushes of the tens, hundreds, thousands and B registers, respectively, thence through brush 517, of the A register which through the fact that this register has been positioned is in some off-normal position, conductor 518, armature and back contact of magnet 505, windings of magnet 505 and relay 503, to battery. Relay 503 and magnet 505 are not energized in series with relay 519. Relay 519 is energized in this circuit and completes a circuit from grounded battery, winding of side switch stepping magnet 520, conductor 521, left armature and back contact of relay 503, side switch brush 522, and its normal contact, outer right armature and front contact of relay 519, to ground. Magnet 520 is energized in this circuit and moves the side switch from its normal position to position 1.

30 It should be noted that the side switch which comprises brushes 507, 522, 586, 581 and 599, is preferably of the same mechanical construction as the register switches. The preferred form of mechanism is similar to that shown and described in Patent No. 1,472,465, issued to O. F. Forsberg and R. M. De Vignier on October 30, 1923.

40 The calling subscriber now sends the second series of impulses in order to position the B register. The first interruption of the line circuit will cause the deenergization of line relay 215, whereupon a circuit is completed from grounded battery, resistance 504, winding of slow-release relay 503, conductors 523 and 524, winding of stepping magnet 525, which controls the B register, conductor 526, side switch arm 507 which is in contact with its first off-normal terminal, conductor 508, left armature and front contact of relay 218, armature and back contact of relay 215, to ground. Stepping relay 525 and relay 503 are energized in this circuit. Relay 503 being slow-to-release, retains its armature attracted until the completion of a series of impulses. Upon the next closure of the line circuit, line relay 215 attracts its armature and magnet 525 releases to advance the B register one step. At the conclusion of the sending of the second series of impulses, the B register will be in position 8.

45 At the conclusion of the series of impulses, line relay 215 remains energized for a relatively long period of time with the

result that relay 503 becomes deenergized. The deenergization of relay 503 completes a circuit from grounded battery, winding of side switch stepping magnet 520, armature and back contact of magnet 520, conductor 521, left armature and back contact of relay 503, side switch brush 522 in its first off normal position, conductor 537, brush 528 of the B register which is now in off-normal position, to ground. Magnet 520 is energized and interrupts its own circuit to cause the advance of the side switch into position 2.

50 In position 2 of the side switch the impulse circuit is diverted to stepping magnet 529 of the thousands register by way of the side switch brush 507 and its second contact, and conductor 530. Relay 503 and stepping magnet 529 are energized in series and relay 503 remains energized during the sending of the series of impulses while stepping magnet 529 causes the advance of the thousands register into position 6.

55 Upon the completion of the sending of the thousands impulses, the side switch is advanced into position 3 over a circuit extending from grounded battery, winding of stepping magnet 520, armature and back contact of magnet 520, conductor 521, left armature and back contact of relay 503, side switch brush 522 and its second contact, thence by way of conductor 531 to the thousands register brush 532 which is now in off-normal position, to ground. The side switch is advanced by means of this circuit to position 3.

60 The setting of the hundreds, tens and units register is accomplished in substantially the manner described since stepping magnet 533, 534, and 535 are successively brought under control of line relay 215 as the side switch arm 507 advances from position to position. Upon completing the settings of registers, the side switch arms will be in contact with the No. 6 off normal terminals.

65 As soon as the A and B registers have been positioned at which time the side switch will be in position 2, a circuit is completed from grounded battery, winding of relay 502, side switch arm 586, and its associated contact, conductor 527, right armature and front contact of relay 218, to ground. Relay 502 is energized and completes a locking circuit for itself extending from its left armature and front contact, conductor 538, conductor 273, upper left contact of sequence switch spring 274, to ground.

70 The setting of the translator switch will now be described. After being set into motion, the translator will hunt for a position controlled by the joint setting of the A and B registers.

75 The construction of the translator switch

120

125

130

is fully described in the patent to Alben E. Lundell, No. 1,550,877, issued Aug. 18, 1925.

As soon as relay 502 is energized a circuit is completed from grounded battery, resistance

5 542, left armature and back contact of relay 543, conductor 544, winding of power magnet 540, conductor 545, inner right armature and front contact of relay 502, to ground. Power magnet 540 is energized and starts the translator switch into 10 operation. The translator will then continue to revolve until test brush 546 which serves the bank designated T reaches contact No. 13, at which time a circuit will be completed from grounded battery, left armature and back contacts of relay 543, the low resistance right winding of relay 543, conductor 547, A register brush 548 and contact number 4, conductor 549, brush 550 15 and its associated terminal No. 8 conductor 551, the No. 13 contact in the arc served by brush 546, conductors 552 and 545, to ground at the armature and front contact of relay 502. The low resistance of the right winding of relay 25 543 shunts the power magnet 540 and brings the translator switch to rest. During the hunting operation of this switch a circuit was in existence for stop magnet 541 from grounded battery, winding of magnet 541, conductor 547, low resistance right winding of relay 543, left armature and back contact of relay 543, conductor 544, winding of power magnet 540, to ground at the armature and front contact of relay 502. The 30 current in this circuit is not sufficient to energize magnet 541 but it does provide enough magnetism to allow stop magnet 541 to act very quickly when the proper terminal set has been found. When the 35 proper terminal is found stop magnet 541 is energized due to the completion of a circuit from magnet 541 in parallel with that just traced for the right winding of relay 543. Magnet 541 is now fully energized and relay 543 is sufficiently energized to attract its armatures, thus breaking the driving circuit of power magnet 540 and causing 40 relay 543 to include both its right and left hand windings in the whole circuit.

50 Referring now to Fig. 3 it will be observed that as soon as relay 543 is energized a circuit is completed from grounded battery, winding of power magnet of sequence switch 200, lower left contact of sequence switch spring 219, conductor 271, left armature and back contact of relay 223, conductor 227, inner right armature and front contact of relay 543, to ground for moving this sequence switch out of position 3 55 and into a position determined by the setting of the translator switch. Sequence switch 200 determines the class and routing of the call and in accordance with its setting will determine the number and kind of impulses to be sent, that is, whether office im-

pulses, whether relay call impulses, whether the call will be directed to a special operator or any of the various combinations essential in a large installation.

The extent of motion of sequence switch 200 will be determined by the point in its operation at which relay 223 is energized. Relay 223 has its circuit successively extended to conductors 228, 229, 230, 231, 232, 233, 234, 235 and 236 as the sequence switch 70 moves through its various positions. These conductors extend to various terminals in the contact banks of the translator. To avoid complexity of the circuits these leads have not been carried down to the translator bank 75 terminals, a single conductor 553 being utilized to indicate the manner in which these contacts will be connected to the arc of contacts which control the positioning of the class register.

80 Since it has been assumed that the call is to be an interoffice full mechanical call, the class register, that is, sequence switch 200, will be brought to rest in position 7. To accomplish this, lead 229 would have to be 85 wired to the No. 13 terminal in the class arc of the contact bank served by the brush set of the translator. When sequence switch 200 reaches position $6\frac{3}{4}$ a circuit is completed from grounded battery, winding of 90 relay 223, upper left and lower right contacts of sequence switch spring 237, conductor 229, conductor 553, No. 13 terminal, brush 554, conductor 555, outer right armature and front contact of relay 543, to 95 ground. Relay 223 is energized and locks through its right armature and front contact and lower contact of sequence switch spring 238, to ground. The energization of relay 223 opens the driving circuit of sequence 100 switch 200 which brings this switch to rest in position 7.

105 The energization of relay 223 also completes a circuit from grounded battery, power magnet of sequence switch 300, upper left contact of sequence switch spring 313, conductors 314 and 315, left armature and front contact of relay 223, conductor 227, inner right armature and front contact of relay 543 to ground for moving this sequence switch out of position 1 and into position 2.

110 As soon as sequence switch 300 reaches position 2 a circuit is completed from grounded battery, right winding of relay 107, left contacts of sequence switch spring 112, inner right armature and front contact of relay 121, sender selector brush 132 and its associated contact, conductor 133, outer right armature and back contact of relay 125 129, contact of sequence switch spring 240, conductors 241 and 316, inner right armature and back contact of relay 317, lower right contact of sequence switch spring 318, winding of stepping relay 320, armature 130 and back contact of relay 321, which is in

parallel with the 0' counting relay, inner left armature and back contact of relay 306, resistance 322, lower contact of sequence switch spring 312, to ground. Relays 107 and 320 are energized in this circuit.

- 10 The energization of relay 107 completes a circuit from grounded battery, power magnet of sequence switch 100, upper left contact of sequence switch spring 116, left armature and front contact of relay 107, lower contact of sequence switch spring 117, to ground, for moving sequence switch 100 out of position 3 into position 4. Relay 107 remains energized in position 4 of sequence switch 100 due to the closure of a locking circuit extending from grounded battery, right winding of relay 107, inner right armature and front contact of relay 107, conductors 110 and 111, lower right contact of sequence switch spring 112, to ground, over the path already described.
- 15 20

In position 4 of the sequence switch a circuit is completed for updrive magnet 134 from grounded battery, winding of magnet 134, lower contact of sequence switch spring 120, inner left armature and front contact of relay 107, lower contact of sequence switch spring 117, to ground.

- 25 30 The energization of stepping relay 320 completes a circuit from ground, upper right contact of sequence switch spring 312, armature and front contact of relay 320, upper contact of sequence switch spring 309, outer left armature and back contact of relay 307, inner right armature and back contact of relay 306, conductor 305, lower left contact of sequence switch spring 304, upper right contact of sequence switch spring 323, contact of sequence switch spring 409, conductor 410, translator brush 556, which is in engagement with the 13th terminal of the T contact bank, thence through the winding of one of the counting relays, to grounded battery.
- 35 40

45 50 In order to simplify the disclosure, the wiring of the counting relays to the various contact sets in the translator banks has not been shown. It will be assumed, however, that, with the translator set with one of its brushes in engagement with the 13th terminal in the T' bank the third brush set of the district switch in the fourth group served thereby will be selected. It will further be assumed that with the same setting the second brush set in the third group served thereby will be selected by the office selector switch.

- 55 60 Under the assumption made, contact No. 13 in the arc served by brush 556 will be connected to the No. 2 counting relay. Contact No. 13 served by brush 557 will be connected to the No. 3 counting relay. Contact No. 13, served by brush 558, will be connected to the No. 1 counting relay and contact No. 13 in the arc served by brush

559 will be connected to the No. 2 counting relay.

The circuit completed upon the energization of stepping relay 320 will then extend from brush 556 to the windings of the No. 2 counting relay to grounded battery. The No. 2 counting relay is energized in this circuit and prepares in a well known manner a circuit for the No. 2' counting relay by way of conductor 324, lower right contact of sequence switch spring 325, to ground. The winding of the No. 2' counting relay, however, is shunted by the ground controlled at the armature and front contact of relay 320 and does not energize at this time.

65 70 75 80 85 90 95 100 105 110 115 120 125 130 As soon as the district brush has advanced a sufficient distance to allow the commutator brush 135 to engage the first conducting segment of commutator 136, stepping relay 320 is shunted down, since the locking circuit of relay 107 now extends from grounded battery, right winding of relay 107, through the inner right armature and front contact of relay 107, conductors 110 and 111, lower right contact of sequence switch spring 112, upper right contact of sequence switch spring 113, commutator 136, commutator brush 135, to ground. The shunting of the stepping relay causes it to deenergize and removes the shunt from the No. 2' counting relay which relay becomes energized and prepares a circuit for the No. 1 counting relay in the well known manner. Only a portion of the counting relays have been shown since the operation of counting relays is well known in the art and it is thought that the disclosure will be sufficient to indicate the method of their operation. When brush 135 leaves the conducting segment of commutator 136 the shunt is removed from stepping relay 320 and this relay again energizes causing the energization of counting relay No. 1. Counting relay No. 1 prepares a circuit for the No. 1' counting relay.

125 130 A third shunting down of the stepping relay will allow the energization of the 0' counting relay and relay 321 in parallel. This circuit extends to ground by way of the armature and front contact of No. 0 counting relay, conductor 324, lower right contact of sequence switch spring 325, to ground. The energization of the 0' counting relay completes a circuit from grounded battery, winding of power magnet of sequence switch 300, upper left contact of sequence switch spring 331, conductor 340, outer armature and back contact of relay 332, conductor 334, inner right armature and back contact of relay 307, armature and front contact of the 0' counting relay, to ground, for moving this sequence switch out of position 2 and into position 4.

The deenergization of relay 321 opens the lower branch of the locking circuit of relay

107 and when brush 135 engages an insulating segment of commutator 136 of the circuit of relay 107 is broken and this relay deenergizes completing a circuit from grounded battery, power magnet of sequence switch 100, lower left contact of sequence switch spring 116, left armature and back contact of relay 107, lower contact of sequence switch spring 117, to ground, moving sequence switch 100 out of position 4 into position 5. The deenergization of relay 107 also opens the circuit of updrive magnet 134 and brings the selector to rest in such position that subsequent upward movement 15 will cause the third set of brushes to be tripped.

As soon as sequence switch 300 reaches position 2, the locking circuits of the counting relays are broken at the upper and lower right contacts of sequence switch spring 325 and the counting relays de-energize.

In position 5 of sequence switch 100 a fundamental circuit is again completed extending from grounded battery, right winding of line relay 107, left contacts of sequence switch spring 112, inner right armature and front contact of relay 121, brush 132 and its associated contact, conductor 133, outer right armature and back contact of relay 239, contact of sequence switch spring 240, conductors 241 and 316, inner right armature and back contact of relay 317, lower right contact of sequence switch spring 318, winding of stepping magnet 320, armature and back contact of relay 321, inner left armature and back contact of relay 306, resistance 322, lower contact of sequence switch spring 312, to ground. Relays 107 and 320 are energized in this circuit, relay 107 completing a locking circuit for itself through its right armature and front contact, conductors 110 and 111, and the contacts of sequence switch spring 112, to ground over the path described. Relay 107 also completes a circuit from grounded battery, power magnet of sequence switch 100, upper left contact of sequence switch spring 116, left armature and front contact of relay 107, lower contact of sequence switch spring 117 to ground for moving sequence switch 100 out of position 5 and into position 6.

In position 5 of sequence switch 100, a circuit was completed from grounded battery, winding of trip magnet 137, lower right and upper left contacts of sequence switch spring 122, conductor 105, outer left armature and front contact of relay 102, to ground. The trip magnet was energized in this circuit to operate the trip rod so that on subsequent upward movement of the brush rod the third set of brushes will be released into engagement with the contact banks served by them.

The above mentioned energization of stepping relay 320 completes a circuit for the No. 3 counting relay extending from grounded battery, winding of No. 3 counting relay, armature and back contact of the No. 3 counting relay, the No. 13 contact of the arc served by brush 557, conductor 530, lower contact of sequence switch spring 411, conductor 421, upper left contact of sequence switch spring 323, lower left contact of sequence switch spring 304, conductor 305, inner right armature and back contact of relay 306, outer left armature and back contact of relay 307, lower contact of sequence switch spring 309, armature and front contact of relay 320, conductors 310 and 311, upper left contact of sequence switch spring 312, to ground. The No. 3 counting relay is energized and prepares a circuit for the No. 3' counting relay.

In position 6 of sequence switch 100 a circuit is again completed for updrive magnet 134, from grounded battery, winding of magnet 134, lower contact of sequence switch spring 120, left armature and front contact of relay 107, lower contact of sequence switch spring 117, to ground. The selector brush and shaft will then move upward to select the desired group. As soon as commutator brush 194 engages a conducting portion of commutator 138 stepping relay 320 is shunted down and deenergizes to allow the energization of counting relay No. 3'.

On the fourth shunting down of stepping relay 320, counting relay 0' in parallel with relay 321 is energized as previously described. The energization of counting relay 0' completes a circuit from grounded battery, winding of power magnet of sequence switch 300, upper left contact of sequence switch spring 331, conductor 340, outer armature and back contact of relay 332, inner right armature and back contact of relay 307, to ground at the armature and contact of the 0' relay. Sequence switch 300 is advanced out of position 2 and into position 4. The energization of relay 321 opens the lower branch of the locking circuit of the relay 107 and when, a moment later, brush 194 engages an insulating segment of commutator 138, the locking circuit of relay 107 is broken and this relay deenergizes. The deenergization of relay 107 completes a circuit from grounded battery, power magnet of sequence switch 100, lower left contact of sequence switch spring 116 left armature and back contact of relay 107, lower contact of sequence switch spring 117, to ground for moving sequence switch 100 out of position 6 into position 7.

With sequence switch 100 in position 7, a circuit is completed from grounded battery, left winding of relay 107, upper contact of sequence switch spring 108, lower right and upper left contacts of sequence

switch spring 109, inner armature and front contact of relay 102, to ground. Relay 107 is energized in this circuit.

When sequence switch 300 reached position 4, a circuit was completed from grounded battery, winding of relay 152, lower contact of sequence switch spring 140, conductor 141, outer right armature and front contact of relay 121, left contact of sequence switch spring 142, sender selector brush 143, and its associated contact, conductor 144, outer left armature and back contact of relay 239, conductor 242, resistance 243, conductor 244, upper contact of sequence switch spring 341, 15 to ground for energizing relay 152.

It is to be observed at this point that when sequence switch 100 reached position 3, a circuit was completed from grounded battery, right hand winding of relay 139, 20 upper left contact of sequence switch spring 140, conductor 141, outer right armature and front contact of relay 121, left contact of sequence switch spring 142, sender selector brush 143 and its associated contact, conductor 144, outer left armature and back contact of relay 239, conductor 242, resistance 243, conductor 244, upper contact of sequence switch spring 341, to ground. Relay 139 was energized in this circuit and at 30 its left armature transferred the holding circuit of relay 102 from the lower right contact of sequence switch spring 103, to the upper right contact of sequence switch spring 103. Relay 139 remains energized 35 until sequence switch 100 leaves position 10.

With relays 107 and 139 energized in position 7 of sequence switch 100, a circuit is completed from grounded battery, power magnet of sequence switch 100, upper left contact of sequence switch spring 116, left armature and front contact of relay 107, upper contact of sequence switch spring 117, right armature and front contact of relay 139, to ground for moving sequence switch 100 out of position 7 and into position 8. As soon as sequence switch 100 reaches position 7½, a locking circuit for relay 107 is completed extending from grounded battery, right winding of relay 107, inner right armature and front contact of relay 107, conductor 110, lower left and upper right contacts of sequence switch spring 145, to test brush 146 and its associated contact, and thence to ground, providing the associated trunk is busy.

It will be assumed that the first trunk in the group is busy. Relay 107, therefore, remains energized and completes a circuit from grounded battery, winding of updrive magnet 134, lower contact of sequence switch spring 120, left armature and front contact of relay 107, lower contact of sequence switch spring 117, to ground. The selector brush set is now moved upwardly 60 over the terminals in the selected group and

when an idle trunk is encountered ground will no longer be found on the terminal associated with test brush 146. This branch of the locking circuit of relay 107 is therefore broken but the relay is held energized 70 an instant longer in order to properly center the brush set due to the closure of the circuit extending from grounded battery, left winding of relay 107, lower contact of sequence switch spring 108, a conducting portion of commutator 149, commutator brush 148, to ground. As soon as commutator brush 148 engages an insulating segment of commutator 149 at which time the brushes will be accurately centered on the selected 75 terminal set, all branches of the locking circuit of relay 107 are opened and this relay deenergizes, causing, in turn, the deenergization of updrive magnet 134 and bringing the selector to rest. The district selector has 80 now been actuated to seize a trunk leading to an idle office selector switch. The deenergization of relay 107 also completes a circuit from grounded battery, power magnet of sequence switch 100, lower left contact of 85 sequence switch spring 116, left armature and back contact of relay 107, lower contact of sequence switch spring 117, to ground for moving this sequence switch out of position 8 and into position 9. 90

With sequence switch 100 in position 9, a circuit is in existence from grounded battery, left winding of relay 107, upper contact of sequence switch spring 108, conductor 164, lower contacts of sequence switch spring 109, 100 right armature and front contact of relay 152 to ground for energizing relay 107. The energization of relay 107 completes a circuit from grounded battery, winding of power magnet of sequence switch 100, upper left contact of sequence switch spring 116, left armature and front contact of relay 107, lower contact of sequence switch spring 117 to ground, for moving this sequence switch out of position 9 and into position 10. 105

During brush and group selection and trunk hunting of the district switch, relay 210 is maintained energized over a circuit extending from grounded battery, winding of relay 210, conductor 245, lower right contact of sequence switch spring 342, outer left armature and back contact of relay 306, conductor 343, sender selector brush 150, and its associated contact, lower left and upper right contacts of sequence switch spring 151, 120 to ground. The function of relay 210 is to prevent the advance of the sender controlling sequence switch until trunk hunting has been completed at the district switch.

As soon as sequence switch 100 leaves position 8, relay 210 is deenergized completing a circuit from grounded battery, power magnet of sequence switch 300, conductors 336 and 337, left armature and back contact of relay 210, conductor 338, lower contacts 125 130

3

of sequence switch spring 339, conductor 340, outer armature and back contact of relay 332, conductor 334, inner right armature and back contact of relay 307, to ground at the armature and front contact of the 0' counting relay. The completion of this circuit moves sequence switch 300 out of position 4 and into position 6.

The operation just described is that which takes place in case an office selector switch is to be operated. In case the office is to be selected directly by the district switch, circuits will become effective to advance sequence switch 300 out of position 4 directly into position 9.

The selections from this point for the office, incoming and final selector circuits are exactly as described in the Patent No. 1,550,377, issued August 18, 1925, to Alben E. Lundell, and since they form no part of this invention the circuits have not been shown and their operation will not be herein described.

As soon as final selections have been made and the incoming selector line relay has been released by the final selector as described in the above identified application, stepping relay 320 is deenergized and the 0' counting relay operates in the well known manner.

The energization of the 0' counting relay at this time completes circuits for relays 239 and 263 extending from grounded battery, the windings of these relays respectively, thence in parallel to conductor 264, inner right armature and front contact of relay 307, which is now in the operated position as described in the aforementioned patent to Alben E. Lundell, armature and front contact of the 0' counting relay, to ground.

Relays 239 and 263 are energized in this circuit and lock up through the inner right armature and front contact of relay 239, to ground, by way of the upper contact of sequence switch spring 238. The energization of relay 239 opens at its outer left armature the holding circuit of relay 152. Relay 152 therefore deenergizes, opening a circuit through the left winding of relay 107, allowing this relay to deenergize. Relay 107, on deenergization completes a circuit from grounded battery power magnet of sequence switch 100, lower left contact of sequence switch spring 116, left armature and back contact of relay 107, lower contact of sequence switch spring 117, to ground for moving sequence switch 100 out of position 10 into position 11.

As soon as sequence switch 100 leaves position 10½ the impulse circuit into the sender by way of leads 129 and 124 is opened at the left contact of sequence switch springs 128 and 125, respectively. As a result of the opening of the impulse circuit relay 215 deenergizes causing in turn the deenergization of relays 217 and 218. With relays 215 and 218 deenergized a circuit is completed from grounded battery winding of relay 259, conductor 265, right contacts of sequence switch springs 266, left armature and back contact of relay 218 armature and back contact of relay 215 to ground. Relay 259 energizes and locks up to ground through its inner left armature and front contact by way of the upper contact of sequence switch spring 238.

The energization of relay 259 completes a circuit from grounded battery, power magnet of sequence switch 300, which is at this time in position, lower right contact of sequence switch spring 331, outer armature and front contact of relay 332, (which is now in its energized position) conductor 334, outer right armature and front contact of relay 307, conductor 368, armature and front contact of relay 263, outer left armature and front contact of relay 259, to ground. Sequence switch 300 is moved out of position 12 (into which position it was moved upon completion of final selections as described in the above identified patent) and into position 13. When sequence switch 300 leaves position 12, the locking circuit of relay 307 is broken and this relay deenergizes.

In position 13 of sequence switch 300 a circuit is completed from grounded battery, lower left contact of sequence switch spring 319, winding of stepping relay 320, armature and back contact of relay 321, inner left armature and front contact of relay 306, right contacts of sequence switch spring 348, resistance 322, lower left contact of sequence switch spring 312, to ground. Stepping relay 320 is now energized by a magnetic field of such polarity that upon release its residual magnetism will be in a direction to aid that normally set up by the completion of the fundamental selecting circuit, and, upon energization, completes a circuit from grounded battery, power magnet of sequence switch 300, lower left contact of sequence switch spring 331, conductors 352 and 310, armature and front contact of relay 320, upper right contact of sequence switch spring 312, to ground, for moving sequence switch 300 out of position 13 and into position 14.

In position 14 of sequence switch 300, circuits are completed to control the selection of talking battery in accordance with the position of class register sequence switch 200. This is accomplished by varying the ratio of the coils in the repeating coil shown in Fig. 2 in accordance with the amount of loading required to produce proper transmission for the type of connection which has been set up. The position of sequence switch 100 will determine the manner in which the various windings of the repeating coil are connected as will be apparent hereinafter.

To accomplish the selection of talking battery the sequence switch 100 is caused to rotate through various positions and while rotating sends revertive impulses into the 6 sender circuit to control counting relays operated in accordance with the setting of sequence switch 200. This is accomplished in the following manner.

Sequence switch 300 is in position 14 of 10 its second revolution. A circuit is completed from grounded battery, right winding of relay 107, left contacts of sequence switch 15 spring 112, inner right armature and front contact of relay 121, sender selector brush 132 and its associated contact, conductor 133, outer right armature and front contact of relay 239, conductor 267, lower left contact of sequence switch spring 318, winding of stepping relay 320, armature and back contact of relay 321, inner left armature and front contact of relay 306, right contacts of sequence switch spring 348, resistance 322, conductor 369, lower contacts of sequence switch spring 370, outer right armature and 25 front contact of relay 357, conductor 371, side switch brush 581, and its associated 9th terminal, conductor 582, right armature and back contact of relay 218, to ground. Relay 107 and stepping relay 320 are energized 30 in this circuit. Relay 107 upon energization completes a circuit from grounded battery, power magnet of sequence switch 100, upper left contact of sequence switch spring 116, inner left armature and front contact of 35 relay 107, lower contact of sequence switch spring 117, to ground, moving this sequence switch out of position 11 and into a position to be determined by the counting relays. Relay 107 completes a locking circuit for itself 40 by way of its inner right armature and front contact, conductors 110 and 111, lower right and upper left contacts of sequence switch spring 112 to ground over the path described. The energization of stepping relay 320 completes a circuit from grounded battery, winding of the No. 0 counting relay, upper left hand contact of sequence switch spring 268, left armature and back contact of relay 213, conductor 299, lower right and 45 upper left contacts of sequence switch spring 363, conductor 394, inner right armature and front contact of relay 306, outer left armature and back contact of relay 307, upper contact of sequence switch spring 309, 50 armature and front contact of relay 320, upper right contact of sequence switch spring 312, to ground. The 0 counting relay is energized in this circuit and prepares a circuit for the 0' counting relay.

When sequence switch 100 leaves position 11½ a circuit is momentarily closed from grounded battery, right winding of relay 107, inner right armature and front contact of relay 107, conductor 110, left contacts of sequence switch spring 145, to ground. Step-

ping relay 320 is shunted down in this circuit and allows the 0' counting relay in parallel with relay 321 to be energized in a well known manner. Relay 321, upon energizing, opens the lower branch of the circuit of relay 107 70 and, when sequence switch 100 leaves position 11½, the upper branch of the holding circuit of relay 107 is broken and this relay deenergizes, opening the driving circuit of sequence switch 100 and causing this sequence switch to come to rest when it reaches position 12.

During the selection of talking battery, the holding circuit of relay 121 is no longer controlled by the outer left armature and front contact of relay 102 since the sequence switch 100 has left position 11. Due to the energization of relay 107 a holding circuit, however, now extends by way of the upper right contact of sequence switch spring 140, conductor 141, outer right hand armature and front contact of relay 121, lower right contact of sequence switch spring 142, outer right armature and front contact of relay 107, conductor 147, lower right and upper left contacts of sequence switch spring 145, to ground. When talking selection is completed and relay 107 deenergizes as previously described, relay 121 is deenergized and at its inner left armature removes ground from the terminal associated with test brush 115 so that the sender is now selectable by other sender selectors. The removal of ground from test conductor 205 allows relay 202 to become deenergized. A circuit is then completed from grounded battery, winding armature and back contact of side switch stepping magnet 520, conductor 521, left contact of relay 503 side switch brush 522, and its associated 9th terminal, conductor 583, outer right armature and back contact of relay 202, to ground. Magnet 520 is energized in this circuit and advances the side switch into its 10th position. A circuit is then completed from grounded battery, 110 winding of the power magnet of sequence switch 200, lower left contact of sequence switch spring 219, conductor 270, side switch brush 581 and its 10th contact, conductor 582, right armature and back contact of relay 218 to ground. The completion of this circuit moves sequence switch 200 out of position 7 and into position 16. When sequence switch 200 leaves position 15 relays 239, 263 and 259 are deenergized. In position 16 the operated winding of relay 502 is shunted down due to the closure of the circuit from grounded battery, resistance 598, conductor 584, lower left and upper right contacts of sequence switch spring 220, conductors 271 and 270, side switch brush 581 and its associated contact, conductor 582, right armature and back contact of relay 218, to ground. Relay 502 is deenergized causing the deenergization of relay 543. As 130

soon as relay 502 is deenergized a circuit is completed from grounded battery, power magnet of sequence switch 200, lower right contact of sequence switch spring 219, conductor 272, left armature and back contact of relay 502, conductors 538 and 273, upper contact of sequence switch spring 274, to ground, moving sequence switch 200 out of position 16 and into position 17.

10 It should be noted that the locking circuit for relays 306 and 332 is broken as soon as sequence switch 200 leaves position 15. The deenergization of relay 306 causes in turn the deenergization of relays 317 and 357.

15 The deenergization of relay 543 completes a circuit from grounded battery, power magnet of sequence switch 300, lower right contact of sequence switch spring 313, conductor 376, outer right armature and back contact 20 of relay 543, to ground for moving sequence switch 300 out of position 14 and into position 1.

In position 17 of sequence switch 200 with the side switch of Fig. 4 in position 10, circuits are completed for restoring the registers. The units register is the first to be restored in a circuit extending from grounded battery, resistance 504, winding of slow-to-release relay 503, conductors 523 and 524, 25 winding of units register stepping magnet 535, armature and back contact of magnet 535, register brush 512 and its off-normal contact, conductor 221, right contacts of sequence switch spring 220, conductors 271 and 30 270, side switch brush 581 and its associated contact, conductor 582, right armature and back contact of relay 218, to ground. Relay 503 and magnet 535 are energized. Magnet 535 interrupts its own circuit until the units 35 register has advanced into its normal position at which time, no further circuit being found for magnet 535, this magnet remains deenergized with the units register in its normal position.

40 The tens register is next to be restored. A self interrupting circuit for its stepping magnet is completed from grounded battery, resistance 504, winding of slow-to-release relay 503, conductors 523 and 524, winding of 45 tens register stepping magnet 534, tens register brush 513 and its off normal contact, thence through units register brush 512 and its normal contact to conductor 221, to ground over the path described. Under the 50 control of magnet 534 the tens register is restored to its normal position. The hundreds, thousands, B and A registers are restored in substantially the same manner which it is thought will be obvious without further description.

60 The translator switch does not have a normal position but remains in the position to which it is last set until put into reoperation.

As soon as the registers are completely restored, a circuit is completed from grounded battery, winding of side switch stepping magnet 520, armature and back contact of magnet 520, conductor 521, left armature and back contact of relay 503, side switch brush 522 and its 10th off-normal contact, conductor 585, A register brush 517 and its normal contact, and thence through brushes 516, 515, 514, 513, and 512 and the normal contacts of the B, thousands, hundreds, tens, and units registers respectively, in series, to conductor 221, then to ground over the path previously described. This circuit energizes magnet 520 which advanced the side switch into position 11 from whence it is driven to its normal position in a self-interrupting circuit leading through brush 581 to ground, at the right armature and back contact of relay 218. The registers and their controlling side switch have now all been restored to 85 their normal positions.

A circuit is now completed from grounded battery, power magnet of sequence switch 200, upper left contact of sequence switch spring 219, conductor 275, side switch brush 581 and its normal contact, conductor 582, right armature and back contact of relay 218, to ground. The completion of this circuit moves sequence switch 200 out of position 17 and into position 1.

The sender and all of its associated apparatus are now in their normal condition and are ready for reuse upon seizure by other districts.

After the incoming selector applies ringing current and the called subscriber answers, polarized relay 160 was energized over a circuit extending into the incoming selector. The energization of relay 160 completes a circuit from grounded battery, winding of charge relay 152, right contacts of sequence switch spring 109, conductor 164, armature and front contact of relay 160, contact of sequence switch spring 166, to ground. Relay 152, is energized in this circuit and locks up through the upper left and lower right contacts of sequence switch spring 109 and its right armature and front contact to ground, until sequence switch 100 leaves position 18.

The connection is now completed and the subscribers may converse. The talking conductors of the calling subscriber's line are connected through to the left hand winding of repeating coil 162 as soon as sequence switch 100 reaches position 11 and they remain so connected in position 12 of sequence switch 100. Battery is supplied to the calling subscriber's line through the windings of the repeating coil. Supervisory relay 167 is included and energized in this circuit. Relay 139 is a differentially wound relay and is maintained energized in positions 2

to 11 of sequence switch 100 by a circuit from grounded battery, left hand winding of relay 139; upper right contact of sequence switch spring 122, to ground. In positions 6 1 to 10 of sequence switch 100, a circuit is in existence through the right winding of relay 139; but since this circuit includes the resistance 243 in Fig. 3, the magnetism set up in the right winding of relay 139 is not 10 sufficient to overcome the polarity of that set up in the left winding and therefore relay 139 remains energized. When sequence switch 100 reaches position 10½ the supervisory relay 167 is energized and the 15 holding circuit of relay 139 now extends through its left winding, armature and front contact of relay 167, and the right armature and front contact of relay 139, to ground. When sequence switch 100 reaches position 20 11 the circuit of the left winding of relay 139 is entirely dependent on the relay 167.

When the conversation is completed and connection is no longer desired, the calling subscriber replaces his receiver. Relay 167 25 deenergizes and causes in turn the deenergization of relay 139.

A circuit is thereupon completed from grounded battery power magnet of sequence switch 100, conductor 168; upper right and 30 lower left contacts of sequence switch spring 169, right armature and back contact of relay 139 to ground, moving sequence switch 100 out of position 12 into position 18.

As sequence switch 100 reaches position 35 17 a circuit is completed from grounded battery, winding of sender selector downdrive magnet 184, armature and back contact of relay 185, lower contact of sequence switch spring 186 to ground. The sender selector brush shaft is returned to its normal position by magnet 184. As soon as brush 183 makes contact with segment 182 on the 40 downward movement of the brush shaft a circuit is completed from grounded battery, winding of relay 185, right contacts of sequence switch spring 188, conductor 187, commutator segment 182, brush 183 to ground. Relay 185 energizes in this circuit 45 breaking the circuit of downdrive magnet 184 and bringing the sender selector brush shaft to rest in its normal position.

In position 18 of sequence switch 100 a circuit is completed from grounded battery, winding of downdrive magnet 178, conductor 191, contact of sequence switch spring 192, armature and back contact of relay 188 to ground. The district brush shaft is returned to its normal position by magnet 178. As soon as brush 148 makes contact 55 with the commutator segment 179 during the downward motion of the district brush shaft, a circuit is completed from grounded battery, winding of relay 188, contact of sequence switch spring 189, conductor 190,

commutator segment 179, brush 148 to ground. Relay 188 is energized in this circuit. If upon the return of the district shaft the sender selector shaft has also been returned to normal, brush 180 is in contact with commutator segment 197 and a circuit is completed from grounded battery winding of power magnet of sequence switch 100, lower right contact of sequence switch spring 116, conductor 193, commutator segment 197, brush 180, conductor 195, armature and front contact of relay 188 to ground, for moving sequence switch 100 out of position 18 and into position 1. If, however, the district brush shaft returns to normal before the sender selector brush shaft, the sequence switch 100 will remain in position 18 until the return of the sender selector to normal.

As soon as the sequence switch 100 leaves position 17 the battery supplied on the sleeve terminal of the line switch is cut-off and the cut-off relay of the called line is deenergized, allowing the calling subscriber's line switch to be restored to its normal position. The deenergization of relay 102 also removes the busy ground condition from the test terminal of the line switch to render the district switch selectable by other hunting line switches.

The release of the calling subscriber's individual line switch takes place as follows: As soon as sequence switch 100 leaves position 17, battery is no longer supplied to conductor 104 and cut-off relay 3 is deenergized. A circuit is completed from grounded battery, winding, armature and back contact of stepping magnet 4, lowermost armature and back contact of cut-off relay 3, left armature and back contact of line relay 2, off-normal contact 13, to ground. Magnet 4 is energized in this circuit and interrupts its circuit to cause the advance of the line switch. Magnet 4 continues to interrupt its own circuit to advance the line switch into its normal position. When the line switch reaches its normal position, off-normal contact 13 is opened and the line switch is brought to rest in readiness for re-operation.

This completes the description of a call 115 initiated by a calling subscriber. However, it is sometimes necessary that an operator complete a call for a calling subscriber who finds difficulty in dialing. When such occasion arises, the operator must have access to the same apparatus as the subscriber would ordinarily have. Therefore, when the operator receives a signal from the calling subscriber whose line terminates at her position, she inserts the plug 35 into jack 36, Fig. 1. A circuit is closed from grounded battery, winding of relays 37 and 34, sleeve contacts of plug 35 and jack 36 to ground. 120 125

The energization of relay 34 causes the illumination of supervisory lamp 38 and the energization of relay 37 prepares a circuit for relay 33 which is completed upon the 5 closure of the tip and ring of the cord. This circuit extends from grounded battery through the left winding of relay 33, left armature and front contact of relay 37, upper winding of repeating coil 29, tip contacts of plug 35 and jack 36 through the 10 loop of the subscriber's station, ring contacts of jack 36 and plug 35, lower winding of repeating coil 29, right armature and front contact of relay 37, right winding of relay 33 to ground. The energization of 15 relay 33 in this circuit places a shunt circuit around lamp 38, extinguishing it and also supplies talking battery to the calling line. Upon ascertaining the number desired by 20 the calling subscriber, the operator inserts plug 23 into jack 21 at her position and operates dialing key 25. A circuit is then completed for operating the line relay in line switch 40 as was described above for a 25 station to station call. Since the same type of apparatus is used in line switch 40 as in the subscriber's line switch the same designations will be used for both. The operation for selecting the district is then the same as 30 that described in relation to a calling subscriber. After the sender has been selected in the manner described dialing tone is given to the operator. The operator then proceeds to manipulate her dial to send out series of 35 impulses. A circuit is in existence from grounded battery, resistance 27, lower contact of dial 26, upper contact of dialing key 25, plug 23 and jack 21, upper armature and front contact of cut-off relay 3, brush 6 and its 40 associated contact 10 of the line switch, conductor 127, upper left contact of sequence switch spring 128, conductor 129, sender selector brush 130 and its associated contact, conductor 131, right armature and back 45 contact of relay 213, high resistance intermediate winding of relay 213, conductor 298, brush 599 of the side switch and its associated normal contact to ground. On the first operation of the dial, relay 213 energizes 50 in this circuit and locks up over a circuit extending from grounded battery, right winding of relay 213, right armature and front contact of relay 213, intermediate winding of relay 213 to ground, over the path described. The energization of relay 213 is the signal to the sender that an operator and not a subscriber is dialing, 55 since relay 213, as will be remembered, was not energized over the subscriber's line. 60 This was due to the fact that pulsing relay 215 was included in the circuit of relay 213 and there was insufficient current flowing in the circuit. The circuit for pulsing now extends from grounded battery, winding of relay 215, conductor 216, sender selector brush 65 120

123 and its associated contact, outer left armature and front contact of relay 121, conductor 124, lower left contact of sequence switch spring 125, conductor 126, contact 12 and brush 8, innermost lower armature 70 and front contact of relay 3, jack 21, plug 23, lower operated contact of dialing key 25 to ground at the upper contact of dial 26. The operator now dials and the operation of the circuit is exactly the same as above described 75 for a calling subscriber until the selection of talking battery. It will be noted here that upon the completion of dialing key 25 is restored to its normal position. 80

As is well known, when an operator originates a call, talking battery is supplied from the operator's set so that it is necessary in making talking selection that the district repeating coil be cut out of the circuit. This is accomplished because of the energization 85 of relay 213 above described. As will be remembered in the description of the selection of talking battery for a subscriber's call, sequence switch 100 was caused to rotate through various positions, sending revertive 90 impulses to the sender circuit and controlling counting relays operated in accordance with the setting of sequence switch 200. With sequence switch 300 in position 14 of its second revolution, a circuit is completed from 95 grounded battery, right winding of relay 107, left contacts of sequence switch spring 112, inner right armature and front contact of relay 121, sender selector brush 132 and its 100 associated contact, conductor 133, outer right armature and front contact of relay 239, conductor 267, lower left contact of sequence switch spring 318, winding of stepping relay 320, armature and back contact of relay 321, inner left armature and front contact of relay 306, right contacts of sequence switch 105 spring 348, resistance 322, conductor 369, lower contacts of sequence switch spring 370, outer right armature and front contact of relay 357, conductor 371, side switch brush 110 581 and its associated 9th terminal, conductor 582, right armature and back contact of relay 218 to ground. Relay 107 and stepping relay 320 are energized in this circuit. Relay 107, upon energization, completes a 115 circuit from grounded battery, power magnet of sequence switch 100, upper left contact of sequence switch spring 116, left armature and front contact of relay 107, lower contact of sequence switch spring 117 to ground, for moving this sequence switch out of position 11 and into a position to be determined by the counting 120 relays. Relay 107 completes a locking circuit for itself by way of its inner right armature and front contact, conductors 110 and 111, and the contacts of sequence switch spring 112, to ground, over the path described. The energization of stepping relay 320 completes a circuit from grounded bat- 125 130

tery, winding of the No. 3 counting relay, back contact of No. 3' counting relay, left armature and front contact of relay 213, conductor 299, lower right and upper left contacts of sequence switch spring 363, conductor 394, inner right armature and front contact of relay 306, outer left armature and back contact of relay 307, upper left contact of sequence switch spring 309, armature and front contact of relay 320, upper right contact of sequence switch spring 312 to ground. The No. 3 counting relay is energized in this circuit and prepares a circuit for the 3' counting relay. The successive counting relays 2, 2', 1, 1' and 0 are energized in succession in the well known manner while sequence switch 100 is advancing. When sequence switch 100 reaches position 14½, a circuit is momentarily closed from grounded battery, right winding of relay 107, inner right armature and front contact of relay 107, conductors 110 and 111, left contacts of sequence switch spring 145 to ground. Stepping relay 320 is shunted down in this circuit and allows the 0' counting relay in parallel with relay 321 to be energized in the well known manner. Relay 321, upon energizing, opens the lower branch of the circuit of relay 107 and when sequence switch 100 leaves position 14½ the upper branch of the holding circuit of relay 107 is broken and this relay deenergizes, opening the driving circuit of sequence switch 100 and causing this sequence switch to come to rest on reaching position 15.

The operation for restoring the sender circuit is now the same as when a subscriber originated the call. It is to be noted now that the talking circuit extending through the district does not pass through the repeating coil. This talking circuit may be traced from grounded battery, right winding of relay 30, upper right winding of repeating coil 29, upper normal contact of dialing key 25, tip contacts of plug 23 and jack 21, upper armature and front contact of cut-off relay 3, brush 6 and contact 10 of the line switch, conductor 127, upper right contact of sequence switch spring 128, brush 154 and its associated contact 153, through the office, if employed, incoming and final selector circuits, through the called subscriber's station set, contact 158 and brush 157, upper contact of sequence switch spring 125, conductor 126, brush 8 and contact 12 of the line switch, innermost lower armature and front contact of cut-off relay 3, ring contact of jack 21 and plug 23, lower normal contact of dialing key 25, lower right windings of repeating coil 29, left winding of relay 30, to ground. Relay 30 is energized in this circuit and opens at its armature and back contact a circuit of lamp 31, extinguishing this lamp as an indication

to the operator that the connection has been completed.

The parties at the calling and called stations may now converse. Talking battery, is supplied to the calling party through the 70 windings of relay 33, front contacts of relay 37, and the left windings of repeating coil 29. Talking battery is supplied to the called party through the windings of the relay 30 over the talking circuit previously 75 traced.

When a conversation is completed and connection is no longer desired, the receivers at the calling and called stations are replaced on their switchhooks. The circuits 80 through relays 33 and 30 are opened, causing the deenergization of these relays. The deenergization of relay 33 removes the shunt circuit around lamp 38, again lighting this lamp as an indication to the operator that the calling subscriber has completed his call. Plug 35 is then removed from jack 36, causing the deenergization of relays 34 and 37. Relay 34 upon deenergizing, opens a circuit through lamp 38, extinguishing it. The deenergization of relay 30 closes an obvious circuit through lamp 31 as an indication to the operator that the called subscriber has replaced his receiver on the switchhook. Plug 23 is removed from jack 21 and the 95 line switch circuit is restored in the same manner as that described for a call originated by a subscriber.

It should be particularly noted that the control of the usual selection of talking battery is under relay 213. This is effected by connecting conductor 299, leading from the counting relays to the contacts of stepping relay 320, through the armature and back contact of relay 213. When this relay is 105 normal selection may be made in the usual manner, but, upon the energization of relay 213, the connection to the counting relays for the usual selection is opened at its back contact.

What is claimed is:

1. In a telephone exchange system, incoming lines of various classes, link circuits, means to connect one of said link circuits with any one of said incoming lines, means 115 associated with said link circuit to vary at will the transmission characteristics thereof, and means common to said link circuits for controlling said first means in accordance with the character of the incoming line to which said link circuit has been connected.

2. In a telephone exchange system, incoming lines of various classes, outgoing lines, link circuits, means to extend an incoming line to one of said outgoing lines by means of one of said link circuits, a repeating coil associated with said link circuit, means associated with said link circuit for either including or excluding said repeating coil for varying the transmission characteristics in 130

said link circuit and means common to said link circuits for controlling said first means in accordance with the class of incoming line to which said link circuit has been connected.

5. 3. In a telephone exchange system, incoming lines of various classes, outgoing lines, a link circuit to be used in establishing connection between an incoming line and an outgoing line, a repeating coil associated with said link circuit, said repeating coil comprising a primary winding and a secondary winding, a switching device for varying the ratio of the number of turns of 10 said secondary winding to the number of turns of said primary winding, means to vary the operation of said switch in accordance with the character of the outgoing line to which connection has been extended, and 15 means for including said repeating coil in said link circuit or excluding it therefrom in accordance with the character of the incoming line.

4. In a telephone exchange system, incoming lines of various classes, outgoing lines, a link circuit to be used in establishing connections between an incoming and an outgoing line, a repeating coil comprising a primary winding and a secondary winding, 20 a switching device for varying the ratio of the number of turns of said secondary winding to the number of said primary winding, a single sending device common to said incoming lines, means for positioning said 25 switching device under the control of said sending device, and means to vary the operation of said sending device in accordance with the character of the incoming line to which connection has been extended.

40. 5. In a telephone exchange system, incoming lines of various classes, a link circuit, means to connect said link circuit with any one of said incoming lines, a register sender common to said lines, means to vary the 45 transmission characteristics of said link circuit in accordance with registrations set up in said sending device, and discriminating means controlled in accordance with the character of the incoming line to which connection has been extended by the link to 50 determine whether or not said registration shall be effective to control said variation.

55. 6. In a telephone exchange system, incoming lines of different classes, a link circuit, means to connect said link circuit to any one of said incoming lines, a register sender

common to said lines, means to set up registrations in said sender under the control of any of said lines, means operative when one class of calling line is connected to said link 60 circuit to vary the transmission characteristics of said link circuit in accordance with said registrations, and means operative when another class of calling line is connected to said link circuit to cancel the effect of said 65 registrations.

7. In a telephone exchange system, incoming lines of different classes, a link circuit, means to connect said link circuit to any one of said incoming lines, a register sender common to said lines, means to set up registrations in said sender under the control of any of said lines, means operative when one class of calling line is connected to said link 70 circuit to vary the transmission characteristics of said link circuit in accordance with said registrations, and means operative when another class of calling line is connected to said link circuit to cancel the effect of said 75 registrations and to produce different transmission characteristics in said link circuit from those which would have been produced under the control of said registrations.

8. In a telephone exchange system, incoming lines of various classes, outgoing lines, 80 link circuits for interconnecting said lines, a repeating coil associated with each said link circuit, and a relay common to said link circuits automatically controlled in accordance with the class of incoming line to which said 85 link circuit has been connected for including said repeating coil in said link circuit or excluding it therefrom for the purpose of controlling the transmission of said interconnected lines.

9. In a telephone exchange system, link circuits, outgoing lines, a line incoming to a link circuit from a subscriber's station, a line incoming to said link circuit from an operator's position, means common to a plurality of said link circuits to differentiate between said lines, means to extend one of said incoming lines to said outgoing line by means of said link circuit, a repeating coil, and means to include or exclude the repeating coil of said link circuit in accordance with the operation of said differentiating means.

In witness whereof, I hereunto subscribe my name this 31 day of October A. D., 1923.

GEORGE THOMPSON.
